UNITED STATES PATENT OFFICE.

WATT L. MORELAND, OF LOS ANGELES, CALIFORNIA.

HEATER FOR MANIFOLD-INTAKES.

1,309,539.

Specification of Letters Patent.

Patented July 8, 1919.

Original application filed March 20, 1916, Serial No. 85,369. Divided and this application filed November 12, 1917. Serial No. 201,585.

To all whom it may concern:

Be it known that I, WATT L. MORELAND, a citizen of the United States, residing at Los Angeles, in the county of Los Angeles 5 and State of California, have invented certain new and useful Improvements in Heaters for Manifold-Intakes; and I do hereby declare the following to be a full, clear, and exact description of the invention, such as 10 will enable others skilled in the art to which it appertains to make and use the same.

This invention relates to improvements in intake manifolds for internal combustion engines and more particularly to a starting 15 apparatus for initially heating the combustible fuel drawn into the engine when the latter is cold.

It is one of the objects of the present invention to provide a simple, practical and 20 efficient and reliable starting apparatus in combination with an intake pipe of an internal combustion engine; and a further object is to provide for the ready control of the combustible fluid passing through the 25 starting apparatus.

With these and other objects in view the invention consists of certain novel constructions, combinations and arrangements of parts as will be hereinafter described relative to the embodiment of the invention 30 illustrated in the accompanying drawing.

The figure is a vertical, central sectional view through the intake manifold connection from the carbureter to the manifold 35 head of an internal combustion engine.

In the apparatus disclosed there is provided means for controlling the initial heat of the gaseous mixture to facilitate the starting of a cold engine, and while the engine 40 is cold heating the fluid by means comprising an electric heater so as to be capable of heating a portion or all of the gaseous mixture which enters the intake manifold indicated at 8. The preferable form of the heating apparatus is shown in the accompanying 45 drawing.

A flue or gas pipe 17, extended from the carbureter a portion of which is shown at 14, is formed with a by-pass extension 31, 50 usually in tubular form as here indicated, and having ports 32 and 33 near the upper end and lower end thereof for establishing communication between the piping 17 and the said by-pass extension 31.

55 A throttle valve 34 may be mounted in the

pipe 17 between said ports 33 and 32 which, when closed will prevent the passage of the mixture thus drawn through said pipe 17 and will direct the same through the said by-pass 31. The throttle is carried by a stem 60 35 which projects through an opposite wall of the pipe 17 and which has a lever 36 secured to one end thereof by which the throttle valve may be operated. When said valve is open it will extend parallel with the axis 65 of the pipe 17 and thus permit the mixture to reach the manifold or head 8, without having to pass through the by-pass extension 31.

Within the said by-pass extension 31 is 70 mounted a suitable electric heating device made up of resistance wires or filaments 37 which are secured at their ends to disks 38 and 39, preferably of insulating material. At their upper ends the said wires 75 or filaments engage a disk 40 which is mounted between the insulating disks 38 and 41. The wires 37 also pass through a metallic disk 42. Both the disks 40 and 42 engage the metal of the by-pass extension 80 31 at their edges so as to establish electric connection with the metal of the piping which forms a ground upon the engine. The lower ends of the wires or filaments 85 37 also pass through a metallic disk 43 and engage a second metallic disk 44, the latter disk being held between the insulating disk 45 below the same and insulating disk 39 above the same. The disks 43 and 44 in this instance are made smaller than the 90 bore of the by-pass extension and do not form any electrical connection with the metal thereof, but on the contrary are insulated therefrom. A rod 46 connects the disks at the upper and lower ends of the 95 filaments or wires 37, the said rod passing through an insulating sleeve 47 at the top so as to be completely insulated from the upper set of disks, while at the lower end said rod is in the electrical contact with the 100 disk 43. A reduced stem 48 on the upper end of said rod extends through an insulating sleeve 49 in the cap piece 50 which closes the upper end of the by-pass extension, and projects far enough beyond the said sleeve to 105 form a binding post for an electrical conductor or wire 51. A nut 52 on said binding post securely holds the conductor or wire 51 in place. The conductor 51 extends to any suitable source of electricity not 110

shown and a current may be sent through the wires 37 to ground for heating the resistance wires 37 whenever desired.

When the throttle 34 is closed a circuit 5 may be completed through the said resistance so that a fuel mixture that passes through the by-pass will be heated and thoroughly gasified in sufficient quantities to insure the starting of the engine. After 10 the engine has been well started the throttle 34 is opened and the current of electricity through the resistance is discontinued.

This application is a division of my application filed March 20, 1916, Serial Number 15 85,369.

What is claimed is:

1. An apparatus for heating carbureted air for starting internal combustion motors, comprising a manifold section having lateral ports and having a shutter intermediate its ends to direct flow of air through said lateral ports thereof, a heating chamber extending along one side of the section and communicating through said ports and 20 forming a by-pass for the carbureted air, and electrical resistance coils in the by-pass 25

chamber whereby the flowing air may be heated prior to entry to the motor, the said coils arranged in an organized unit bodily removable from the chamber.

30

2. An apparatus for heating carbureted air for starting internal combustion motors, comprising a manifold section having lateral ports and having a shutter intermediate its ends to direct flow of air through 35 said lateral ports thereof, a heating chamber extending along one side of the section and communicating through said ports and forming a by-pass for the carbureted air, and electrical resistance coils in the by-pass 40 chamber whereby the flowing air may be heated prior to entry to the motor, the said coils arranged in an organized unit bodily removable from the chamber, said unit comprising a rod on which is mounted spaced 45 disks to which the ends of the coils are connected, the coils extending from disk to disk beside and spaced from the rod so as to be wholly exposed to the passing air.

In testimony whereof I affix my signature.

WATT L. MORELAND.
